UNION AIR TIGHT PATENTED 1851
WARNICK & LEIBRANDT PHILA

UNITED STATES PATENT OFFICE.

FREDERICK SCHULTZ, OF PHILADELPHIA, PENNSYLVANIA.

DESIGN FOR AN AIR-TIGHT STOVE.

Specification forming part of Design No. 364, dated April 1, 1851.

To all whom it may concern:

Be it known that I, FREDERICK SCHULTZ, of Philadelphia, in the county of Philadelphia and State of Pennsylvania, have invented or produced a new and original Design for a Stove called "The Union Air-Tight;" and I do hereby declare that the following is a full and exact description of the same, reference being had to the annexed drawings, making part of this specification.

Figure 1 is a front elevation of the stove. Fig. 2 is a view of the top plate. Fig. 3 is a view of the bottom plate. Fig. 4 is a front elevation of one of the legs.

The front elevation represents a base or foundation composed of an ornamented plate, A, supporting a series of steps, upon which stands a paneled and enriched stylobate, B, supporting a row of ribbed columns, C, in bas-relief, and upon which columns rests an entablature whose architrave D is enriched with wreaths E, with branches entwined and shields F between them, the frieze G being enriched with stars, one over each shield, the cornice H of said entablature, which is enriched in the manner represented, projecting boldly over the frieze, and crowned with a series of horizontal moldings, I, of the ovolo, cavetto, and fillet contour and enriched with moldings. The walls or plates J between the ribbed columns

are paneled and enriched with foliated ornaments K in bas-relief. The heads of these panels are of a semicircular form. The main body of the heater is of a rectangular form, having its front and back and sides ornamented in manner substantially similar to the front plate, Fig. 1. The top plate, H, which forms the cap and cornice, is enriched with foliated ornaments—such as those represented at L, M, and N—and paneled, as at O, P, and Q, the panels O P being ornamented with flowers R, the panels Q being blank. The bottom or base plate, A, is also ornamented with raised figures in relief, as shown at A', Fig. 3, and with raised letters composing the words "Union Air-Tight, Patented 1851, Warnick & Leibrandt, Phila." The legs are ornamented with flowers T and shields V, as represented more clearly in Fig. 4.

What I claim as my invention, and desire to secure by Letters Patent, is—

The design for stoves, substantially as herein set forth, and represented in the accompanying drawings.

In testimony whereof I have hereunto signed my name before two subscribing witnesses.

FREDK. SCHULTZ.
